UNITED STATES PATENT OFFICE.

EDWARD L. STUCK, OF PLOVER, WISCONSIN.

FORCE-FEED LUBRICATOR.

No. 879,210.

Specification of Letters Patent.

Patented Feb. 18, 1908.

Application filed June 2, 1906. Serial No. 319,941.

To all whom it may concern:

Be it known that I, EDWARD L. STUCK, white, citizen of the United States, residing at Plover, in the county of Portage and State of Wisconsin, have invented certain new and useful Improvements in Force-Feed Lubricators, of which the following is a specification.

This invention relates to improvements in lubricators of the type in which the oil is fed by mechanical force to the parts to be lubricated.

The special object of the improvements which form the subject matter of this application is to provide a sight and force feed lubricator of economical construction which will not be liable to get out of order, and in which the oil will be fed in quantities desired.

In the accompanying drawing which forms a part of this application I have shown a vertical section of a lubricator constructed according to my invention.

Referring to the details of the drawing, A represents a glass cylinder which is set in a casting B, and is closed at the top by a cover G, said casting and cover being secured together by one or more tie-bolts g¹. Through the center of the cover is an opening g¹, below which is suspended a cup-shaped strainer g² through which the oil is poured into the cylinder.

The casting B is cup-shaped in its general form, and is formed with an upwardly extending vertical tubular portion b¹, with a central opening in its bottom and with two lateral openings extending through suitable bosses formed on its sides at opposite points, all of said openings being threaded internally to receive parts to be described.

Secured to the bottom of the casting B, by a collar b² which has a threaded engagement with a flange b⁷ on the casting, is a glass sight-feed cup C which receives water, glycerin or other suitable liquid through which the drops of oil may be seen in the usual manner.

Screwed into the central opening in the bottom of the casting B, is a pump-casing or tube d¹ which extends downwardly into the cylinder A, and downwardly into the cup C, as shown. The upper end of the tube d¹ is threaded externally and has screwed thereon a cap d⁷, which, with suitable packing, forms a stuffing-box for a plunger D, which is mounted in the tube and, except where

grooved as at d⁴, fits closely the walls of the latter. In the side of the tube near its lower end is a port d⁵ which communicates with the interior of the cup C. From the portion of the tube d¹ within the cylinder A, extends a horizontal tubular branch d², the inner end of which communicates with the tube through a suitable port, and the outer end is externally threaded to receive a valve-chamber b³, which is screwed into an opening in the side wall of the casting B. This chamber is internally threaded to receive a pipe coupling b⁶ upon which may be screwed any suitable pipe (not shown) leading to the parts to be lubricated.

There are ports between the interior of the coupling b⁶ and the chamber b³, and between said chamber and the tubular extension d². The latter port is controlled by a ball-valve b⁴ which is normally held on its seat in the chamber by an expansion coiled spring b⁵. The passage between the inner end of the extension d² and the pump tube d¹ is controlled by a ball valve d³ which is normally held on its seat by the expansion coiled spring d⁶.

In the extension b¹ is mounted a piston f¹ the upper end of which has secured thereto a rod F which extends upwardly through the cylinder A and the top G, and terminates in a button by which it may be easily turned manually. About midway its length the rod is threaded and engages a link d⁸, one end of which is pivoted to the plunger D and the other end is secured by a pin d⁹ to a drive-rod e¹ which is connected with and driven by a crank e¹ on the inner end of a shaft E. This shaft is journaled in a box e⁴ which is screwed into an opening in the side of the casting B, passes through a stuffing-box e⁵ and has a drive pulley e² on its outer end, the latter to be driven by any suitable means.

Screwed into an opening in the bottom of the casting B just below the extension b¹ is a tube f⁴, which extends downwardly into the cup C and has its lower end bent upwardly. In the upper end of this tube is a port which communicates with the lower end of the extension b¹, and said port is controlled by a ball-valve f² which is held against its seat by an expansion coiled spring f³ secured in the tube f⁴.

A lubricator constructed substantially as described will operate as follows:—Oil being placed in the cylinder A and power being applied to the pulley e², the rod e¹ and plun-

ger D will be reciprocated by the combined action of the shaft E, crank e^1 and link d^1 ; oil will enter the extension b^1 through the hole in its side, and be expelled therefrom by the 5 downward stroke of the piston f^1 , the pressure being sufficient to unseat the valve f^2 against the tension of the spring f^3 . Upon the upward movement of the plunger D, some of the oil resting on top of the water in 10 the cup C will be drawn into the extension d^1 , and will be expelled from same by the downward stroke of said plunger, the oil flowing along the groove d^4 in the plunger, unseating the valve d^5 , passing through the extension 15 d^6 with sufficient pressure to unseat the valve b^6 and so pass to the connection b^6 .

It will be apparent that by screwing up or down the rod F the amount of oil entering the extension b^1 will be controlled, and therefore 20 by regulate the flow of oil through the other parts.

Having thus described my invention what I claim, is:—

In a lubricator, the combination of an oil- 25 supply receptacle having a sight-feed cup removably secured thereto, a casing arranged

in said receptacle and projecting into said feed-cup, said casing having inlet and outlet ports, a plunger arranged in said casing and adapted to alternately cover and uncover 30 the inlet port, a laterally extending extension for the casing having an outlet duct, a valve yieldingly held in said outlet duct, there being a groove in the side of said plunger arranged to afford a constant communication between said outlet port and the space below said plunger, a piston and a cylinder arranged in said receptacle, the casing for the bottom of said cylinder extending through 35 said receptacle, a link having fixed connection with said plunger, a crank shaft, a drive-rod pivoted to said link, a piston rod for said piston adjustably secured to said link, a conduit for conducting oil from said cylinder to 40 said sight-feed cup, and a valve yieldingly held in said conduit.

In testimony whereof I affix my signature in presence of two witnesses.

EDWARD L. STUCK.
